UNITED STATES PATENT OFFICE.

FREDERIC P. GATES, OF HARTFORD, CONNECTICUT, ASSIGNEE TO THE ARROW ELECTRIC COMPANY, OF HARTFORD, CONNECTICUT, A CORPORATION OF CONNECTICUT.

ELECTRIC-LAMP SOCKET.

1,245,699.

Specification of Letters Patent. Patented Nov. 6, 1917.

Application filed April 11, 1916. Serial No. 90,416.

To all whom it may concern:

Be it known that I, FREDERIC P. GATES, a citizen of the United States of America, and residing at Hartford, in the county of 5 Hartford and State of Connecticut, have invented a certain new and useful Improvement in Electric-Lamp Sockets, of which the following is a specification.

My invention relates to electric lamp sockets and particularly to the switch mechanism therefor, the object of my invention being to provide a simple and efficient switch mechanism which may be installed within the confines of a socket body and be operated 15 by a reciprocating push plate.

In the accompanying drawings,

Figure 1 is a vertical section through a socket in which my invention is embodied in one form;

Fig. 2 is a plan of the socket body and switch with the upper insulating button of the latter removed;

Fig. 3 is a section on the line 3-3, Fig. 2;

Fig. 4 is a side elevation of the socket body;

Figs. 5 and 6 are plan and side elevation respectively of the switch-operating push plate;

Figs. 7 and 8 are similar views of the 30 switch member; and

Figs. 9 and 10 are perspective views of the wire terminals for the socket.

Referring to the drawings, the socket here illustrated comprises a metallic casing of 35 common type having cap 11 and shell 12, with insulating linings 13. Within the casing and supported thereby is the socket body comprising a pair of insulating buttons 14 and 15. These buttons are recessed in register on opposite sides to form channels 16 and 17 through which the wires may be led to the respective wire terminals 18 and 19. The terminal 18 is formed from sheet metal, the offset strap 20 of which overlies the base 45 flange of the screw shell side contact 21 to which it is secured by the screws 22 which pierce the button 15 of the socket body. The other wire terminal 19 has an offset strap 23 which is let into a channel 24 formed in 50 the outer face of the button 15 and separated from the base of the screw shell by an insulating disk 25.

The meeting faces of the two buttons 14 and 15 are recessed to form a closed switch 55 chamber 26. The base of switch terminal

27, arranged within this chamber, overlies the strap 23 and is mechanically secured in position as well as electrically connected to the strap 23 by a securing screw 28 which pierces the button 15. The coöperating 60 switch terminal 29 is arranged diametrically opposite the terminal 27 in the switch chamber and its base is connected by screw 30 to the base 31 of the center contact 32 seated in recess 33. Passing vertically through the 65 switch chamber 26 and piercing both buttons is the switch spindle 34 on which the switch bar 35 oscillates. The switch bar 35 comprises a pair of contact wings 36, 37, which are adapted to engage the switch terminals 70 27 and 29 to complete the circuit to the center contact 32. This switch piece is mounted upon a bearing sleeve 38 and an associated plate 39 to which it is riveted by the overturned upper edge of the sleeve 38. The 75 switch spring 40 is coiled upon the sleeve 38 and its free ends lie on opposite sides of the lug 41 extending downwardly from the plate 39. The lower opposite margins of this lug 41 are offset at 42, 43, to form stops 80 as will be hereinafter more fully explained. An arm 44 of the plate 39 is provided at its free end with a pair of downwardly angled flanges 45 adapted to act as detents.

Coöperating with the switch bar 35 is the 85 reciprocating push bar 46 provided at its opposite ends with push buttons 47 which project through suitable guide apertures in the the casing and socket body. The push bar 46 is centrally slotted at 48 to permit the passage therethrough of the switch spindle 34, the extent of reciprocation being thus limited. A marginal lug 49 is provided on the push bar and is engaged between the free 90 ends of the switch spring 41 but inside the 95 arc subtended by the lug 41 of the switch bar plate 39. A second lug 50 is struck up from the push bar 46 and projects into the path of the flanges 45 on the arm 44 of the plate 39.

The operation of this switch mechanism will be readily understood. Upon the transverse displacement of the push bar 46 in the direction of the arrow α (Fig. 2) the lug 49 engaging one end of the switch spring 41 100 serves to tension the latter, since the switch bar plate 39 and its spring-engaging lug 41 are temporarily detained through the engagement of the flanges 45 on the arm 44 thereof with the upstanding lug 50 on the 105 110

- push bar. As soon as the latter has traveled sufficiently far for the lug 50 to escape the flange 45, the switch bar plate is free to rotate under the influence of the switch spring 41. The switch bar thus moves to the "off" position with a snap action and the current is broken through the switch at the two switch terminals simultaneously. The movement of the switch to the "on" position is merely the reverse of that just described, the second flange 45 of the detent arm 44 engaging the opposite side of the detent lug 50 on the push bar 46 until the desired tension for the switch spring 41 has been attained.
- 15 The arc of oscillation of the switch bar 35 may be made commensurate with the current to be broken by varying the length of the offset ears 42, 43, on the lug 41 of the switch bar plate 39. These ears form stops which engage the edge of the push bar 46 and thus determine the extent of oscillation of the switch bar in opposite directions.
- 20 Various modifications of details of construction will readily occur to those skilled in the art without departing from what I claim as my invention.

I claim as my invention:

1. In an electric switch of the type described, an oscillating contact bar, an associated escapement plate rigid therewith, said plate having integral therewith a pair of arms extending at an angle to each other, a switch-actuating spring having its free ends engaged on opposite sides of one of said arms and a movable detent member temporarily engaged by the opposite sides of the other arm.
2. In an electric switch of the type described, an oscillating contact bar, an associated escapement plate, a bearing sleeve forming a rivet to hold said contact bar and plate rigid with relation to each other, said

escapement plate having integral therewith a pair of arms extending at an angle to each other, a switch-actuating spring having its free ends engaged on opposite sides of one of said arms and a movable detent member temporarily engaged by the opposite sides of the other arm.

3. In an electric switch of the type described, an oscillating contact bar, an associated escapement plate rigid therewith, an arm on said escapement plate having stop lugs, a switch spring for throwing said contact bar, the ends of said spring engaging opposite sides of the said arm, in combination with a reciprocating push bar for energizing said spring, said stop lugs impinging against the sides of a portion of said push bar to limit the oscillation of the switch bar.

4. In an electric switch, a base comprising a pair of insulating buttons spaced apart on their meeting faces to form a closed switch chamber, a switch spindle passing through said chamber and piercing said buttons, and a switch mechanism mounted on said spindle within the chamber, said mechanism comprising an oscillating contact bar having rigid therewith a spring-engaging arm and an escapement arm, a switch spring coiled on the spindle, a reciprocating push bar passing through the chamber and having a lug cooperating with the escapement arm of the contact bar and a second lug engaging the switch spring to energize the same.

In testimony whereof I have signed my name to this specification, in the presence of two subscribing witnesses:

FREDERIC P. GATES.

Witnesses:

FRANK ALLEY,
BENJ. WILKINS.
